UNITED STATES PATENT OFFICE

2,490,830

FLASHLIGHT

Frank W. Norton, Chicago, Ill.

Application November 1, 1945, Serial No. 625,985

3 Claims. (Cl. 240—10.68)

1

The invention relates to improvements in flashlights and has for its primary object the provision of an improved flash light arrangement protecting the light bulb from damage when not in use, and also giving a widely diffused light when used.

Other objects will appear hereinafter.

The invention consists of combinations and arrangements of parts hereinafter described and claimed.

The invention will be best understood by reference to the accompanying drawings forming a part of this specification, and in which:

Fig. 1 is a longitudinal section of a flash light embodying the invention and shown with the parts in position of non-use;

Fig. 2, a similar view showing the parts in the position assumed when the flash light is in use;

Fig. 3, a partial longitudinal section of a modified form of construction showing the parts in position of non-use;

Fig. 4, a similar view of the flash light shown in Fig. 3, but showing the parts in position of use; and

Fig. 5, a partial longitudinal section of another modified form of construction.

The embodiment of the invention illustrated in Figs. 1 and 2 comprises an elongated casing 10 of insulating material having a light opening 11 in the center of one end. A battery 12 is slidably arranged in casing 10 and a cap 13 is arranged to force the said battery forwardly in said casing when desired. An electric light bulb 14 is arranged as shown, with its metallic base 15 fitting snugly but slideably in a metallic bushing 16 in said casing, the central contact of said light bulb making electrical contact with the central contact 17 of the battery 12, as shown. A spiral-helical spring 18 is arranged around the light bulb 14 and normally holds said light bulb and said battery in retracted positions, the spiral-helical form of the spring permitting of maximum movements of the light bulb through the light opening 11 because of the fact that the coils of the spring fit one within the other when the spring is fully contracted so that under such circumstances the spring occupies a plane of the thickness of the one strand of the wire of the spring.

When it is desired to use the flash light, the cap 13 is turned to force the battery 12 forwardly in the casing 10 until the shell 19 of the battery makes electrical contact with the inner end of the bushing 16 and the light bulb 14 is protruded through the light opening 11, thereby closing the

2

electrical circuit through the light bulb and exciting the same. When the light is discontinued, the cap 13 is operated to permit the retraction of the light bulb 14 and battery 12 to the influence of the spring 18.

In the construction disclosed in Figs. 3 and 4, the casing 20 is metallic and the light bulb base 15 slides in a slideable sleeve or bushing 21 of insulating material. The cap 13 carries a metallic disc 22, so that when the battery 12 and light bulb 14 are forced forwardly by the action of the cap 13, electrical contact is effected between the casing 20 and the shell 19 of the battery, and between the casing 20 and the metallic base 15 of the light bulb, through the medium of the spring 18, thereby exciting the light bulb when the same is protruded from the casing, with results substantially as above described.

In the modification illustrated in Fig. 5, the casing 23 is of insulating material and the end thereof having the light opening 11 is in the form of a screw cap 24. The bulb portion 14 of the light bulb is in contact with the helical expansion spring 18' which serves to yieldably hold the bulb 14 in neutral position until moved forward by the positive pole 17 of the said battery. The base 15 of the light bulb slides in a slideable sleeve or bushing 26, having a contact flange 27 at its inner end adapted and arranged to make contact with the insulating sleeve or cover of the battery 12 when said battery is advanced. A connecting bar 28 is extended, as shown, the full length of the battery 12 which may consist of a number of cells if desired, and the said bar is provided at its forward end with an inwardly turned flange 29 adapted and arranged to make contact with the flange 27 of the sleeve 26.

At its rear end, the connecting bar 28 is provided with an inwardly extending flange 30 resting against the rear end of the shell of the battery 12, and pressed against said shell by a disc 31 at the inner end of an operating plug 32, threaded in the rear end of the casing, as indicated. In this instance, when the battery 12 is advanced to bring the flange 29 in contact with the flange 27, the light bulb 14 will be protruded from the casing and electrical connection established with the light bulb, as will be readily understood, with results as before.

While I have illustrated and described the preferred form of construction for carrying the invention into effect, this is capable of variation and modification without departing from the spirit of the invention. I therefore do not wish to be limited to the precise details

disclosed, but desire to avail myself of such variations and modifications as fall within the scope of the appended claims.

I claim:

1. A flash light having a casing of insulating material in which the light opening is at one end of said casing; a screw cap on the other end of said casing; a battery slidably arranged within said casing in contact with said screw cap; a metallic bushing having external threads mounted in said casing in spaced relation with said light opening; a cylindrical bore through said bushing in concentric alignment with the inner wall of said casing to slidably entertain the base of an electric light bulb; an electric light bulb in said bushing; a shoulder on said light bulb envelope forwardly of said base; a spiro-helical spring projecting forwardly from said shoulder; a filament envelope of less diameter than said shoulder extending into said spiro-helical spring; and an inwardly facing ledge in circumferential alignment with said light opening in said case providing a seat for the outer end of said spiro-helical spring.

2. A flash light having a tubular casing of insulating material; a light opening at one end of said casing; an adjustable closure on the other end of said casing; a battery slidably arranged within said casing in contact with said adjustable closure; a metallic bushing having a cylindrical bore in concentric alignment with said casing adjacent said light opening; a light bulb having a metallic base slidably arranged within said bore, having its center contact in touch with

30

the center contact of said battery; a circular shoulder on the glass envelope of said bulb; a helical spring expanded forwardly of said circular shoulder; a glass filament envelope of less diameter than said circular shoulder extending forwardly into said helical spring; a circumferential ledge within said casing around said light opening engaging the outer end of said helical spring; there being sufficient slidable movement of said battery and bulb assembly to allow the metallic shell of the battery to connect with the metallic bushing and close the circuit through the light filament.

3. The construction specified in claim 1 in which the said metallic bushing is adjustable longitudinally of said casing.
